APPARATUS FOR CONTROLLING RECOIL

Robert H. S. Hughes, Baltimore, Md., assignor
of one-half to Milton Roberts, Baltimore, Md.

Application March 6, 1937, Serial No. 129,497

2 Claims. (Cl. 89—14)

My invention relates to a device for controlling recoil and it is particularly adapted for use in controlling the recoil of firearms. In connection with the use of the device on firearms it is 5 desirable to eliminate climb, since climb interferes with accurate shooting, in particular where the shots are delivered in rapid succession.

It is an object of my invention to eliminate, or minimize climb, as well as whip. 10 It is a further object of my invention to provide a recoil control which is simple in construction, light, durable, and cheap to manufacture.

With these and other objects in view, which 15 may be incident to my improvements, the invention consists in the parts and combinations to be hereinafter set forth and claimed, with the understanding that the several necessary elements comprising my invention may be varied 20 in construction, proportions and arrangements, without departing from the spirit and scope of the appended claims.

In order to make my invention more clearly understood, I have shown in the accompanying 25 drawing means for carrying the same into practical effect without limiting the improvements in their useful applications to the particular constructions which, for the purpose of explanation, have been made the subject of illustration.

30 In the drawing:

Figure 1 is a longitudinal sectional view taken through the axis of the bore of the firearm and the axis of the bore of the gas seal of my device.

Figure 2 is a view taken along the line 2—2 35 of Figure 1 looking in the direction of the arrows.

Figure 3 is a view taken along the line 3—3 of Figure 2 looking in the direction of the arrows.

Figure 4 is a view similar to Figure 2 of a modification of my device showing a series of gas 40 ports arranged in groups.

Referring to the drawing I have shown a muzzle 1 of a firearm provided with screw threads 2 adapted to mesh with screw threads 3 formed on the inside of a collar 4, of my recoil control 45 which I have generally indicated by the numeral 5.

The recoil control comprises a body portion 6 formed with a combustion chamber 7. The body is formed with a forward extension 8 having a seal port 9 extending therethrough from the combustion chamber and with an annular shoulder 11 extending from the inner end of the seal port to the side wall of the chamber, and also with discharge ports, leading rearwardly and outwardly from the forward part

of the chamber adjacent the shoulder, the prolongation of the outer sides of said ports substantially coinciding with the periphery of said shoulder. These ports, 12', 13, 14, 15, as shown in Figs. 1 and 2, are arranged in an arcuate series, around the top and sides of the device, but there are no ports in the lower part 12 of the body. 5

In order to eliminate climb as much as possible, the ports at the top of the recoil control 10 5 make a larger angle with the axis of the bore of the firearm than do the ports lower down the sides of the recoil control. In general the construction is such that the ports make a progressively smaller angle from the top to the 15 bottom. Referring to Figure 2, for instance, the construction is generally such that the port 12' makes a greater angle with the axis of the bore of the firearm than the ports 13. The ports 13 make a greater angle than do the 20 ports 14; and the ports 14 make a greater angle than do the ports 15.

This arrangement provides a large downward thrust by reason of the relatively great angle of the ports at the top of the recoil control. The 25 greater the angle of the ports at the top of the recoil control the less these ports contribute to the elimination of recoil against the shoulder of the user of the gun, in case a shoulder arm is used; but also the greater the angle the upper 30 ports make with the axis of the bore of the firearm, the more climb is eliminated.

Referring to Figure 4 I have shown a modification in which ports are grouped in series. At the top of the device, I have shown two ports 35 20 which are shown grouped together. Below these there is on either side considerable space 21 in which there are no ports, and then there are two ports 22 on the other side. This arrangement permits the recoil control to be used 40 under conditions where a recoil control having equally spaced ports all around the body could not be used. The grouping of ports, for instance as is shown in Figure 4, is of particular value in using the device on guns mounted on 45 shipboard where a stanchion of the ship, or other parts of the gun or ship might interfere with the free flow of gases from the ports.

While I have shown and described the preferred embodiment of my invention, I wish it to 50 be understood that I do not confine myself to the precise details of construction herein set forth by way of illustration, as it is apparent that many changes and variations may be made therein, by those skilled in the art, without de- 55

parting from the spirit of the invention, or exceeding the scope of the appended claims.

I claim:

- 5 1. A recoil controlling device for guns adapted to fire projectiles, comprising a body adapted for attachment to the muzzle of a gun barrel, said body having a gas chamber therein and having an inlet port and a seal port at the rear and forward ends of said chamber, respectively, and a shoulder extending laterally from the inner end of the seal port to the side wall of the chamber, said device having an arcuate series of discharge ports extending rearwardly and outwardly from the forward part of the chamber, the prolongation of the outer sides of the several ports substantially coinciding with the periphery of said shoulder, the axes of the discharge ports in the upper part of the device being at a greater angle to the axis of the seal port than are the axes of the discharge ports in the sides of the device.
- 10 2. A recoil controlling device for guns adapted

to fire projectiles, comprising a body adapted for attachment to the muzzle of a gun barrel, said body having a gas chamber therein and having an inlet port and a seal port at the rear and forward ends of said chamber, respectively, and a shoulder extending laterally from the inner end of the seal port to the side wall of the chamber, said device having an arcuate series of discharge ports extending rearwardly and outwardly from the forward part of the chamber, the prolongation of the outer sides of the several ports substantially coinciding with the periphery of said shoulder, the axes of the discharge ports in the upper part of the device being at a greater angle to the axis of the seal port than are the axes of the discharge ports in the sides of the device, and the axes of the discharge ports progressively making a smaller angle with the axis of the seal port from the top of the body downward.

ROBERT H. S. HUGHES.
